UNITED STATES PATENT OFFICE.

CHARLES H. HAESELER, OF PHILADELPHIA, PENNSYLVANIA.

ROTARY PERCUSSIVE TOOL.

1,074,116.

Specification of Letters Patent. Patented Sept. 30, 1913.

Application filed May 27, 1913. Serial No. 770,135.

To all whom it may concern:

Be it known that I, CHARLES H. HAESELER, a citizen of the United States, residing in the city of Philadelphia, county of Philadelphia, and State of Pennsylvania, have invented certain Improvements in Rotary Percussive Tools, of which the following is a specification.

My invention is designed to provide improved mechanism for automatically rotating drills, bits or upsetting devices of percussive tools, particularly the cutting devices of pneumatic hammer drills.

Mechanisms heretofore employed for rotating drills have been defective in their operations because, among other reasons, they have lacked the capacity to effect the desired turning movement, on account of the close relation of the motor to its work and the character of the means by which it is actuated. Particularly in producing the turning movement by a fluid motor, the cylinder and piston employed have been disposed and connected so that the clutch mechanism to be operated fails to engage upon defective actions or short strokes of the piston which result from the condensation of moisture in the air, the accumulation of dust, and the limited time the fluid acts upon the piston.

The leading purposes of my improvements are to avoid these defects of the prior art and to provide an efficient mechanism capable of effecting the desired intermittent rotary movement, which I am enabled to do by means comprising a clutch having a member directly connected to the drill chuck in front of the main cylinder containing the percussion piston, a fluid motor having a cylinder containing a piston at the rear of the main cylinder, a lever having a short arm connected with a member of the clutch and a long arm connected with the motor piston so that the reductions in the stroke of the latter shall have comparatively slight effect on the action of the clutch insufficient to prevent its intended operation, and means for maintaining the motive fluid on the motor piston throughout the greater part of the length of the strokes of the percussion piston for the purpose of obtaining a complete throw of the lever and the full action of the clutch.

This mechanism is characterized by efficiency and reliability of action due in great

measure to the comparatively long stroke of the piston operating the lever, the multiplied length of the lever's power arm compared with its work arm operating the clutch whereby adequate force is provided for securing the turning movement, and the maintenance of the motive fluid on the piston during practically the full stroke of the percussion piston.

In the accompanying drawings, Figure 1 is a part sectional elevation of a hammer drill embodying my improvements; Fig. 2 is an elevation of the same at right angles to that shown in Fig. 1; Fig. 3 is a sectional view taken on the line 3—3 of Fig. 2; Fig. 4 is a sectional view taken on the line 4—4 of Fig. 3; Fig. 5 is a sectional view taken on the line 5—5 of Fig. 3; Fig. 6 is a sectional view taken on the line 6—6 of Fig. 3; Fig. 7 is a diagrammatic sectional view of the developed apparatus showing the relation of the parts with the percussion piston at the beginning of its forward stroke; Fig. 8 is a diagrammatic sectional view of the developed apparatus showing the relation of the parts with the percussion piston at the beginning of its reverse movement.

The hammer drill illustrated comprises the main cylinder 1 having the head 3 at the rear end thereof and the reduced cylinder 4 fixed to the head 5 at the forward end thereof. A piston 6 is adapted to reciprocate in the cylinder 1 and is provided with the hammer 8 adapted to reciprocate in the cylinder 4. A chuck is provided by a head 9 which engages the forward end of the cylinder 4, has fixed thereto the sleeve 10 revolvable within the cylinder, and is screwed into the sleeve 11 revolvable on the cylinder, the outer sleeve having the circular flange or ring 12 at the top thereof and the ratchet teeth 13 thereon. A drill shank 14 extends upwardly through the head 9 and sleeve 10 into the cylinder 4 so that the rear end thereof may receive the blows of the hammer 8 which drives the stem forward through such sleeve, the latter conforming to the octagonal contour or flat surfaces of the stem. A collar 15 incases the flange 12 and is provided with an inwardly extending flange 16 which engages the aforesaid flange; the collar being supported and normally held in engagement with flange 2 on the cylinder 4 by rods 55 (which pass

through lugs 57 on the collar, and between lugs 56 and through lugs 58 on the main cylinder) and springs 59 held by such rods in engagement with the flange 16. A clutch 5 ring 17, provided with ratchet teeth 18 which engage the teeth 13, encircles the cylinder 4, within the collar 15, and is pressed toward the flange or ring 12 by plungers 19 actuated by springs 20, the ring being provided with the stud 22 extending through the collar and having the cylindrical bearing 24 journaled thereon. A lever 26 is fulcrumed on the stud 27 fixed to the cylinder 1 and has at the end of its short arm a yoke 25 which engages in conforming relation with the spherical surface of the bearing 24. This lever has at the end of its long arm a bearing 28 journaled by means of the stud 29 connected to the piston 30 having recessed heads 31 and 32 adapted to reciprocate in the respective cylinders 33 and 34, these cylinders being fixed to a head 60 sleeved on the rear head of the cylinder 1. The cylinders 33 and 34 have screwed in the ends thereof the heads 31' and 32' provided with plugs 31" and 32" adapted to enter the recessed heads.

Motive fluid is introduced by the conduit 37 in the head 60, to the cylinder 1, through 30 the screen 47', passage 38, chamber 39, passage 40 communicating with the rear end of the cylinder and passage 41 communicating with the forward end thereof. The chamber 39 contains a ball valve 47 movable in the seat 50 so as to control the communication of the passage 38 with the passages 40 and 41, the valve being normally held by motive fluid flowing through the ports 49 in position for closing the passage 41. A passage 35 40 connects the rear end of the cylinder 1 with the cylinder 34 (which is provided with the exhaust port 36'), and the passages 43 and 44 connect the cylinder with the atmosphere at points between the points of connection 45 of the passages 35 and 36 with such cylinder.

In operation the tool is held in position by the handle 60' fixed to the head 60 and motive fluid is admitted through the passages 37, 38, 39, and 40 to the interior of the cylinder 1 to drive the piston 6 and hammer 8 forward and strike the drill shank 14. When this piston, in its forward movement, uncovers the passage 35, motive fluid is admitted therethrough to the cylinder 33 and 55 moves the piston 30 to the position shown in Fig. 7. The lever 26 is thus rocked on its fulcrum 27 and turns the clutch ring 17, which positively engages and turns the complementary clutch ring 12, thereby turning 60 the parts 11, 9, 10 and 14 through the desired angle. When the advancing piston 6 uncovers the exhaust port 43 and establishes its connection with the passage 35, the cylinder 33 exhausts therethrough, and, the passage 44 then being covered, fluid in the cylinder

der 1 in front of the piston 6 is compressed and acts through the passage 41 to move the valve 47 so as to establish communication between the passages 38 and 41. The motive fluid now flows through the passage 41 to the cylinder 1 to move the piston 6 in the reverse direction and through the passage 36 to the cylinder 34 to move the piston 30 to the position shown in Fig. 8. This movement of the piston 30 rocks the lever 26 and turns the clutch ring 17 backward, the teeth 18 riding over the teeth 13.

Having described my invention, I claim:

1. In a percussive tool, the combination of a cylinder, a piston adapted to reciprocate therein, a chuck connected with and revolvable relatively to said cylinder, clutching means connected with said chuck, clutching means connected with and adapted for engaging and revolving said clutching means first named, means comprising a lever for oscillating said clutching means second named and revolving said clutching means first named, and means whereby the reciprocation of said piston effects the oscillation of said lever. 80

2. In a percussive tool, a main cylinder, a percussive piston adapted to reciprocate therein, a revolvable tool holder, clutching mechanism comprising a revolvable member connected with said holder and an oscillating member adapted for engaging said member first named, means comprising a fulcrumed lever for operating said oscillating member and intermittently turning said revolvable member, a piston connected with said lever, and fluid pressure means whereby said piston first named operates said piston second named. 95

3. In a percussive tool, a main cylinder, a percussive piston adapted to reciprocate therein, a revolvable tool holder, means comprising clutching devices adjacent to the forward end of said cylinder for intermittently turning said tool holder, a lever connected with said means whereby said clutching mechanism is operated, and fluid pressure mechanism adjacent to the rear end of said cylinder whereby said lever is oscillated. 100

4. In a percussive tool, a main cylinder, a percussive piston therein, a revolvable tool holder, means for connecting said tool holder with the forward end of said cylinder, mechanism between the forward end of said cylinder and said tool holder for intermittently turning the latter, a lever for operating said mechanism and turning said holder, a motor in the rear of said cylinder whereby said lever is oscillated, and fluid pressure means whereby said piston operates said motor. 110

5. In a percussive tool, a main cylinder, an auxiliary cylinder connected with the forward end thereof, a percussive piston in said main cylinder, a hammer adapted to be reciprocated in said auxiliary cylinder by said 120

piston, a tool holder connected with and revoluble relatively to said auxiliary cylinder, clutching mechanism adapted to turn on said auxiliary cylinder, said mechanism having a member fixed to said holder and a member movable relatively thereto, a fulcrumed lever whereby said second member is oscillated and said first member revolved in a step by step movement, a motor for oscillating said lever, and fluid pressure means whereby said piston operates said motor.

6. In a percussive tool, a main cylinder, a percussion piston therein, a revoluble tool holder, clutching mechanism having a member fixed to said tool holder and an oscillating member whereby said member first named is turned, a fulcrumed lever for operating said oscillating member, a fluid motor for oscillating said lever, and fluid pres-

sure means operated by said piston whereby said motor is operated.

7. In a percussive tool, a cylinder, a percussive piston therein, a revoluble tool holder, a driving device fixed thereto, an oscillatable device adapted for turning said driving device, a casing containing said devices, a fulcrumed lever, means whereby said lever operates said oscillatable device, a motor for oscillating said lever, and fluid pressure means whereby said piston operates said motor.

In testimony whereof I have hereunto set my hand this 22nd day of May, 1913, in the presence of the subscribing witnesses.

CHARLES H. HAESELER.
